HAIR WAVING APPLIANCE

Anthony La Torraca, Newark, N. J.

Application June 14, 1944, Serial No. 540,177

2 Claims. (Cl. 132—33)

This invention relates to improvements in hair waving appliances; and the invention has reference, more particularly, to an improved and simplified device adapted especially for use in waving hair by the method known to the art as the "cold wave" process which avoids the necessity for use of heat and attendant discomfort to the subject which the use of heat involves.

This invention has for an object to provide a hair waving appliance comprising a base clamp and a mandrel removably mountable thereon, said base clamp being of very simple and compact construction, having a minimum of manipulatable parts, whereby the same can be easily and quickly manipulated and applied in use, and which, when applied to the subject's head, is of minimum weight and bulk.

The invention has for further objects to provide a novel construction of hair waving appliance comprising a base clamp for gripping, in use, a selected tress of the subject's hair as closely as possible to the scalp, whereby to hold such tress subject to preliminary treatment and manipulation by the operator, while at the same time functioning to guard or protect the subject's scalp during such treatment; said clamp having novel means for latching its pivoted clamp bar in holding relation to the tress of hair, which means is self-adjusting to automatically accommodate the hair gripping and holding position of said pivoted clamp bar according to the amount or quantity of hair in the tress thereof selected for treatment; said base clamp being further provided at its ends with upstanding transverse bifurcate posts, the spaced arms of which define upwardly open bearing notches, and the inner sides of said arms carrying arcuate leaf-springs for gripping and retaining the trunnions of a mandrel upon which the tress is wound after preliminary treatment, when said trunnions are entered in said bearing notches so as to operatively couple said mandrel to the base clamp.

Other objects of this invention, not at this time more particularly enumerated, will be understood from the following detailed description of the same.

An illustrative embodiment of this invention is shown in the accompanying drawing, in which:

Fig. 1 is an end elevational view of the base clamp member of the appliance as operatively applied to a tress of hair at a point close to the subject's scalp, whereby the tress may extend therefrom subject to treatment by the operator; and Fig. 2 is a transverse sectional view of the appliance showing the treated tress of hair wound

upon the mandrel member of the appliance and mounted on the base clamp member.

Fig. 3 is a top plan view of the base clamp member; Fig. 4 is a side elevational view thereof; and Fig. 5 is a bottom plan view thereof.

Fig. 6 is a side elevational view of the base clamp member with the mandrel member operatively mounted thereon; and Fig. 7 is an end elevational view of said assembled base clamp member and mandrel member.

Similar characters of reference are employed in the above described views, to indicate corresponding parts.

As shown to best advantage in Figs. 3 to 5 inclusive, the base clamp member of the hair waving appliance according to this invention comprises a main body 10 of suitable width and length. Intermediate its ends, said main body 10 is cut away along one side to provide a longitudinally extending portion of approximately one-half the width thereof and of reduced thickness adapted to constitute a stationary clamp bar 11. Upstanding from the respective end portions of said main body, perpendicularly to the plane thereof, are transverse bifurcate posts 12, the spaced opposed arms 13 of which define upwardly open bearing notches 14, which are aligned with the central longitudinal axis of said main body. Affixed to the free end portions of said arms 13, to extend downwardly therefrom, respectively into and along opposite inner faces of the sides of said notches 14, and thus in opposition one to the other, are inwardly bowed or arcuate leaf springs 15, the purpose of which will be subsequently disclosed.

One end portion of said main body 10 is cut away at its under side to provide a countersunk recess or seat 16 to receive the hinging ear 17 of a pivotally movable clamp bar 18, said hinging ear 17 being pivotally connected with said end portion of the main body by a hinge pin 17'. Said movable clamp bar corresponds in thickness and length to the thickness and length of the stationary clamp bar 11, and is adapted to be swung into and out of the cutaway side of said main body 10, so as to oppose and cooperate with the inner edge portion of said stationary clamp bar when inswung toward the latter.

The top face of said movable clamp bar 18 is provided with a longitudinal guideway channel 19 which extends from its free end toward its pivoted end. Slidably mounted in said guideway channel 19 is a latch bolt 20, the outer side of the free end portion of which is provided with an inclined wedging face 21. The end portion of the main

body 10, opposite to that to which said movable clamp bar 18 is pivotally connected, is provided with a longitudinally disposed latch bolt receiving socket 22, which is opposed to the free end of said movable clamp bar 18 when the latter is in-swung into cooperative relation to said stationary clamp bar 11, and which is adapted to receive engagement of said latch bolt 20, when the same is projected from the end of the thus in-swung movable clamp bar 18. The means for retaining the latch bolt 20 in operative assembled relation to said movable clamp bar, in one illustrative embodiment thereof, comprises a headed keeper stud 23 which is affixed to the movable clamp bar to extend through a longitudinal slot 24 with which the body of said latch bolt 20 is provided. At its inner or rearward end, said latch bolt 20 is provided with a raised boss 25 or other suitable means affording a finger-piece to aid manipulation thereof.

Detachably mountable on the base clamp member is a mandrel 26 having trunnions 27 respectively projecting axially from its opposite ends. The body of said mandrel 26 is of a length to fit and engage between the posts 12 of the base clamp member, and is preferably of the shape shown in Fig. 6, being of maximum diameter at its end portions and tapered from said end portions toward its mid-portion which is reduced in diameter and cross-sectional area. Pivotally connected with one end portion of the mandrel 26 is a hair gripper member 28 which substantially conforms to the side contour of the mandrel, when swung inwardly along a side thereof.

In the use of the appliance for treating a tress of hair by a "cold wave" method, the tress T (see Fig. 1) to be treated is separated from the mass of the subject's hair and the base clamp member is applied thereto. To this end the movable clamp bar 18 is released and swung outward to open position (see dotted representations thereof in Figs. 3 and 5), whereupon the base clamp member is applied close to the scalp of the subject, adjacent to the base of the tress T, and so that the latter may be laid across the inside gripping edge of the stationary clamp bar 11, so as to be disposed between the latter and the open movable clamp bar 18. The tress T having been thus disposed, the movable clamp bar 18 is closed to grip the base of said tress close to the subject's scalp, and is thereupon latched for retention in such gripping relation to the tress by sliding forward the latch bolt 20, whereby to enter its projected end in the receiving socket 22 of the main body 10. In thus engaging the main body 10, the inclined wedging face 21 of the latch bolt 20 will abut a contiguous side of said receiving socket 22, and will not only firmly pinch the engaged hair between the opposed edges of the stationary and movable clamp bars 11 and 18, but, owing to its inclined face, will automatically adjust the gripping position of the movable clamp bar to that best adapted to accommodate and hold the particular amount or quantity of hair making up the base portion of the tress T.

When the base clamp member is applied to the tress and secured in the manner above set forth, said base clamp member will be positioned and retained close to the subject's scalp, not only so as to segregate the tress T from the mass of the subject's hair, but also so as to protectively cover the scalp areas from which said tress T springs.

The segregated tress T extending from the applied base clamp member is now subject to treat-

ment by the operator pursuing a "cold wave" method, which treatment comprises combing or brushing out the extending tress and thereupon applying to and wetting the same thoroughly with

5 a treating liquid of suitable chemical characteristics adapted to facilitate setting of a wave or curl therein after the tress is wound upon the waving or curling mandrel 26.

To wind the tress upon the waving or curling mandrel 26, the hair gripper member 28 is swung or opened out, whereupon the free end portion of the tress T is laid over the mid-portion of said mandrel and said hair gripper member 28 closed thereover to grip and hold such tress end portion.

15 Thereafter, the mandrel 26 is rotated to wind up the tress T thereon and about the gripper member 28, and so as to carry said mandrel to the base clamp member. As the mandrel reaches said base clamp member, mandrel trunnions 27 are respectively entered in the respective notches 14 of the posts 12, and are pressed inwardly so as to ride over the opposed arcuate leaf springs 15 and beyond the bowed mid-portions of the latter until stopped at the bottoms

20 of said notches. It will be obvious from an inspection of Fig. 7, that said springs 15 will releasably retain the trunnions 27 against accidental outward displacement from the notches 14, thereby holding the mandrel and the tress wound 25 thereupon in attached relation to the base clamp member, so that the tress is retained in the described wound relation to the appliance.

The appliance as thus operatively applied to the subject's hair and head is allowed to so remain a sufficient length of time necessary for effective action of the treating solution in setting the wave or curl in the tress, after which the appliance may be removed, and the waved or curled hair may thereupon be dressed by the operator to produce such style of coiffure as may be desired.

In carrying out the "cold wave" method, it is desirable to bring the treating solution in contact with substantially the entire length of the tress under treatment, and then to wind the treated tress as close to the head as possible. The appliance according to this invention is especially designed to attain these ends, since the clamp bars are of minimum thickness, and the means 50 for receiving and holding the mandrel 26 in mounted relation to the base clamp member is such that said mandrel may be brought very close to clamp bars of said base clamp member.

It will be understood that the base clamp member and the mandrel may be made of any suitable material, and especially, except for the springs 15, of non-metallic material, such e. g. as plastics and like materials which are not likely to be deleteriously effected by the treating solutions employed in "cold wave" methods of hair treatment.

Having now described my invention, I claim:

1. A hair waving appliance comprising a base clamp member having a main body cut away 65 along one side intermediate its ends to provide a stationary clamp bar portion, said main body having transverse bifurcate posts upstanding from its respective end portions to provide outwardly open notches, a detachable mandrel member, said mandrel member having trunnions projecting from its opposite ends for confinement within said post notches, whereby to support the same upon and between said posts in closely spaced relations to said main body, yieldable detent means affixed to the opposite

interior walls of said post notches for releasably holding the mandrel trunnions against displacement from said notches, a movable clamp bar pivotally attached by one end to one end portion of said main body, whereby to be swung into and out of the cut away side of said main body in opposition to the inner edge of said stationary clamp bar portion thereof, a latch bolt slidably mounted for longitudinal movements in a countersunk guideway channel provided in the top of said movable clamp bar subject to projection from the free end of the latter, means for retaining said latch bolt in operative assembled relation to said movable clamp bar, a main body post opposed by the free end of said movable clamp bar having a latch bolt receiving

5 socket, and said latch bolt having an inclined outwardly facing wedging portion at its receiving socket engaging end for self-adjustingly securing said movable clamp bar in gripping relation to a tress of hair disposed between the latter and said stationary clamp bar.

10 2. A hair waving appliance as defined in claim 1, wherein said yieldable detent means cooperative with the mandrel trunnions comprises inwardly bowed leaf-springs of less width than the main body posts, said springs being by their outer ends affixed to said posts with their free bowed portions respectively extending into and along opposite interior sides of the post notches.

ANTHONY LA TORRACA.
